UNITED STATES PATENT OFFICE.

JULIEN STRANDERS, OF NEW YORK, N. Y., ASSIGNOR TO HARRY B. KRUGER, OF NEW YORK, N. Y.

DISPLAY DEVICE.

1,002,775.

Specification of Letters Patent. Patented Sept. 5, 1911.

Application filed June 13, 1911. Serial No. 632,842.

To all whom it may concern:

Be it known that I, JULIEN STRANDERS, a subject of the King of Great Britain, and resident of New York, borough of Brooklyn, county of Kings, and State of New York, have invented certain new and useful Improvements in Display Devices, of which the following is a specification.

This invention relates to display-devices of the kind that are intended to be set up in show-windows, and to be arranged in position after they have been opened from their folded or collapsed condition.

The object of the invention is to provide a display-device that is inexpensive to manufacture and which may be folded in convenient shape for shipment and transportation, and also readily opened from the collapsed state to the operative state by the mere movement of the members relatively to each other.

For this purpose the invention consists of display-faces hinged at their front edge and a rear holding-portion or supporting-member hinged at the rear edge; the forward edges of the holding-portion being hinged to the display-faces, the holding portion and display-faces forming in one open position a rectangle, the fold of the display-faces and the fold of the holding-part being arranged on one diagonal line thereof, and the points of hinging of the holding-portion to the display-faces being arranged on the other diagonal.

The invention consists further in arranging a plurality of display faces in the form of a pyramid and continuing the holding-portion from the lowest display face to the uppermost, the parts being so arranged that on the closing of the holding-portion all of the display faces are also folded in their closed position. By this means the display device after folding may be readily and conveniently packed and shipped, and when opened may be readily and quickly placed in position of use.

In the accompanying drawings, Figure 1 is a perspective view of my improved display-device, Fig. 2 is a front-view of the same, on a larger scale, Fig. 3 is a side-view, Fig. 4 is a top-view of the display-device shown in Fig. 2, Fig. 5 is a top-view of the display-device in extended position, and Fig. 6 is a top-view of the display-device in nearly folded collapsed form.

Similar letters of reference indicate corresponding parts throughout the several figures.

Referring to the drawings, a plurality of display faces 7, 8, 9, 10 are arranged one above the other, each set rearwardly from the one immediately below it. The different display faces differ in size, the longest 10 at the bottom and the shortest 7 at the top, each one differing in size from the other in an amount to produce a symmetrical appearance. Each of the display faces is hinged to the supporting-member 11 by means of having the forward end of the supporting-member turned over to form a flap 12 which is secured by glue or other suitable means to the display-faces, it being essential that the hinge thus formed operate freely. The supporting-member 11 is formed of one sheet of material which is folded at the rear edge 13 and at its forward edge is bent over and secured to the display face by the hinge 12.

The display faces are preferably made of one piece and folded at the front edge 14. The edges 13 and 14 are diagonally opposite each other and the hinges 12 are also diagonally opposite each other and these folded edges as also the hinges being readily movable, the supporting-member and the display-faces may be moved relatively to each other to take any position from the position shown in Fig. 5, to the flat folded position approached in Fig. 6, the intermediate position where the parts form substantially a square (Fig. 4) being the operative position in which the device supports itself securely in position against falling over. The supporting-member 11 is provided with steps 15 at each of its arms or leaves and on these steps the different-sized display-faces are supported, which display-faces are secured to the supporting-member in the manner just described by means of the turned-over hinge and the edge 13 of the supporting-member forming a continuous edge from the bottom lowermost display-member to the uppermost. In order to conceal the supporting-member and thereby further enhance the value of the display-device the bottom of each display-face extends slightly below the upper edge of the one below it. It will also be noticed that the point of the display-face to which the supporting-member is hinged, is at the central

part of the display-member whereby the rear edge 13 of the supporting-member and the rear edge 16 of each display-face, are in alignment and proximity when the device is collapsed in the form shown in Fig. 6. Any desired advertising matter (not shown) is printed on the front surfaces of the display-faces.

The device may be made of cardboard throughout, which is of suitable stiffness and at the same time forms folding edges; but it is clear that other yieldable material may be used, the invention consisting particularly in the arrangement of the supporting-member and the display-faces in a square or rectangular arrangement which is collapsible along its diagonals and by means of which it may be folded into flat condition for shipment, and when desired opened into self-sustaining operative form.

It is obvious that changes may be made in the construction without departing from the spirit of the invention.

Having thus described my invention, I claim as new and desire to secure by Letters Patent:

1. A display device consisting of a supporting member provided with a single fold to form a rear edge and a display face provided with a single fold to form a front edge, the supporting member having its free edges hinged to the rear of the display face, whereby the device may be folded into two different collapsed positions, or opened into operative position, the rear edge of the display face being substantially in line with the rear edge of the supporting member when in one of its collapsed positions and having

its supporting member contiguous to the display face when in the other of its collapsed positions.

2. A display-device, consisting of a supporting-member hinged at its rear edge and having a plurality of steps at the front thereof, a plurality of display-faces on the steps of the supporting-member, and a hinge-connection between the front edges of the supporting-member and the rear part of the display-faces.

3. A display-device, consisting of a plurality of display-faces folded so as to form a folded front edge, arranged one above the other, the lower member extending above the lowermost portion of the member immediately above it, a supporting-member folded to form a folded rear edge extending from the lowermost display-member to the uppermost and having steps at its front portion extending below the lowermost edge of each display-member, and turned-over portions at the front edges of the supporting-member secured to the rear side of the display-faces at a point substantially at the middle part of each display-face, whereby when the device is in collapsed or folded position the rear edge of the supporting-member and the rear edges of the display-faces are in line with and in proximity to each other.

In testimony, that I claim the foregoing as my invention, I have signed my name in presence of two subscribing witnesses.

JULIEN STRANDERS.
